Geo. P. Kimmel
ATTORNEY.

UNITED STATES PATENT OFFICE.

WALTER L. BRADY, OF DEHUE, WEST VIRGINIA.

TROLLEY-WIRE HANGER.

Application filed July 11, 1922. Serial No. 574,191.

To all whom it may concern:

Be it known that I, WALTER L. BRADY, a citizen of the United States, residing at Dehue, in the county of Logan and State of West Virginia, have invented certain new and useful Improvements in Trolley-Wire Hangers, of which the following is a specification.

This invention relates to supports for wires and the like, more particularly to a device for suspending electric trolley and like conductor wires in mines, tunnels, and similar localities, but which may be employed in a variety of locations, and has for one of its objects to provide a device of this character which may be quickly installed where required and removed and installed in another locality and thus repeatedly used.

With these and other objects in view the invention consists in certain novel features of construction as hereinafter shown and described and then specifically pointed out in the claim, and in the drawings illustrative of the preferred embodiment of the invention:

Figure 1 is a vertical sectional elevation of the improved device applied.

Fig. 2 is a side elevation of the expandable portion of the improved device.

Fig. 3 is a transverse section on the line 3—3 of Fig. 1.

The improved device comprises a holding element in the form of a tubular stock or body 10 which includes a polygonal shaped lower portion 12, a cylindrical intermediate portion and an upper portion. The lower portion 12 is of a contour to receive a wrench or other tool. At the point of joinder of the lower portion with the intermediate portion the stock is formed with a lateral flange 11. The outer periphery of the upper portion for a part of its length is provided with cutting teeth for a purpose to be hereinafter referred to.

The stock 10 is provided with a plurality of elongated clefts 13 of less length than the length of the stock, and the said clefts 13 extend through the threaded or toothed portion of the stock and provide the upper portion of the stock with outwardly shiftable gripping tongues. The clefts 13 are of greater length than the length of the threaded or toothed portion of the stock, and extend entirely through the latter and are ar-

ranged equi-distant with respect to each other. The clefts are so set up to provide the tongues of gradually decreasing width upwardly.

The threaded portion of the stock is preferably initially tapered externally and also slightly tapered internally, as indicated in Fig. 2, which represents the stock before being applied.

The threads of the stock are preferably of the "rapid" arrangement, as indicated at 14 in Fig. 2, and preferably ratchet shaped transversely or with one face substantially at right angles to the axial line of the stock and the other face oblique to the axial line, to increase the "grip" of the teeth when inserted and rotated in the supporting body.

Disposed within the threaded and cleft portion of the stock is an internally screw threaded tapered sleeve 15, the sleeve adapted to be engaged by the threads of a hanger rod 16 which is connected to a head member 17. The member 17 supports a clamping device, represented conventionally at 18, for holding a trolley wire, a portion of which is represented at 19.

The sleeve 15 is provided with longitudinally directed ribs 20 which extend into one or more of the clefts 13, to prevent rotation of the sleeve while leaving it free to be moved longitudinally of the stock.

In applying the improved device, a hole is bored in the ceiling or wall of the mine, drift, gallery, tunnel, or other place where the trolley wire is to be supported, the latter indicated at 21. The stock 10 having the tapered sleeve 15 in its outer end is then inserted in the bored hole and rotated by a wrench or like implement applied to the portion 12 of the stock to cause the teeth or threads thereof to "bite" into the wall 21 and the rod 16 with the head 17 attached inserted in the stock and its threaded portion engaging in the sleeve. The head member 17 with the trolley wire clamp 18 attached is then rotated to correspondingly rotate the rod 16 and thus apply force to the sleeve longitudinally of the stock to cause the tapered sleeve to expand the "land" portions of the stock between the clefts and thus firmly "anchor" the stock 10 and rod 16, head 17 and trolley wire grip 18 carried thereby to the wall 21. The trolley wire is then applied to

the clamp and the clamp nut 22 rotated to bind the jaws of the trolley clamp upon the wire.

Should any looseness develop the "slack" 5 can be readily taken up by a few turns of the head 17 and the rod 16 carried thereby, as will be obvious.

The device can be easily detached by 10 reversely rotating the clamp nut 22 to release the trolley wire from the clamp 18, reversely rotate the head 17 until the bolt 16 moves the sleeve 15 to the smaller end of the hole bored for the stock, thus permitting the divided portion of the stock to be contracted 15 by its own resiliency and easily removed by reversely rotating by wrench or like implement applied to the portion 12 of the stock.

The location of the improved device may 20 thus be quickly changed as required, during the progress of the mining operations.

The improved device is simple in construction, can be inexpensively manufactured and operates effectively for the purposes described.

25 The preferred embodiment of the invention is disclosed in the drawings and set forth in the specification, but it will be understood that modifications within the scope of the claimed invention may be made in 30 the construction without departing from the principle of the invention or sacrificing any of its advantages.

Having thus described the invention, what is claimed as new is:—

35 A trolley wire hanger comprising a holding element in the form of a tubular stock consisting of a polygonal-shaped lower portion, a cylindrical intermediate portion and an upper portion having its wall slit throughout at a plurality of points to form 40 a series of tongues shiftable outwardly with respect to said intermediate portion and each having its outer face provided with teeth, said stock further including a lateral flange at the point of joinder between said 45 intermediate and lower portions, a head member abutting against said lower portion, a hanger rod carried by the head member and extending up through said stock and having the upper portion thereof threaded, 50 and a tapered sleeve mounted in said upper portion and provided with internal threads engaging with the threads of said rod to provide for the moving of the sleeve downwardly causing thereby the outward shifting 55 of the tongues to engaging position, said sleeve having peripheral ribs engaging between the tongues to arrest rotative movement of the sleeve when moved downwardly 60 by the rod.

In testimony whereof, I affix my signature hereto.

WALTER L. BRADY.
